34 33 INVENTOR
HARRY SEIGMAN

BY *Walton Harrison,*
HIS ATTORNEY

UNITED STATES PATENT OFFICE.

HARRY SEIGMAN, OF NEW YORK, N. Y.

RAZOR DOUBLE STROPPING MACHINE.

Application filed November 28, 1922. Serial No. 603,738.

To all whom it may concern:

Be it known that I, HARRY SEIGMAN, a citizen of the United States, and resident of New York city, in the county of New York and State of New York, have invented certain new and useful Improvements in Razor Double Stropping Machines, of which the following is a full, clear, and concise description.

10 My invention relates to razor double stropping machines, my more particular purpose being to produce a device of this character having two strops, one made preferably of canvas and the other of leather, 15 the device as a whole being so arranged and adapted as to enable the operator to use first one of the strops and then the other, upon an individual razor blade.

More particularly stated, I seek to produce a small machine, operable by hand and made up to sell at a moderate price, the machine being composed of a relatively small number of parts of simple construction, so formed and arranged that either 25 a single razor blade or two such blades may be held within the machine at the same time, and either or both of these blades subjected to the alternate action of the two strops above mentioned; that is to say, the strop 30 made of canvas and the one made of leather.

Reference is made to the accompanying drawing forming a part of this specification, and in which like reference characters indicate like parts throughout the several figures.

Figure 1 is a substantially central vertical section through my device.

Figure 2 is an end elevation of the mechanism appearing in Figure 1.

40 Figure 3 is a fragmentary side elevation of the same.

Figure 4 is a fragmentary side elevation, showing my device as it appears while being changed for the purpose of substituting one strop for the other, for use upon a blade.

Figure 5 is a section on the line 5—5 of Figure 3, looking in the direction indicated by the arrows.

50 Figure 6 is a fragmentary section showing the device in use, after the change contemplated by Figure 4 is made.

Figure 7 is an enlarged fragmentary elevation, corresponding to the left hand portion of Figure 3.

A bail appears at 7, and is provided with a pair of ends 8, turned inwardly. Pivoted to these ends are a pair of bearing plates 9, made of sheet material. A pair of rocking plates are shown at 10 and 11, and are provided with edge portions 12, 13 each bent laterally to the plane of the plate. Engaging these edge portions are a pair of edge portions 14 with which a connecting plate 15 is provided. The connecting plate 15 with its edge portions 14 is made of a single integral piece of sheet spring metal. Thus the two rocking plates 10 and 11 and the connecting plate act collectively as practically a single piece, pivoted at its center upon the bearing plate 9. There are two sets of the rocking plates 10 and 11 and the connecting plates 15. That is to say, these parts are duplicated at the ends of the machine. There are two blade holders 16 and 17, and these are adapted to carry razor blades 18 and 19.

Two rockers are shown at 20 and 21 and are made of sheet metal so as to have a substantially semi-cylindrical form. These rockers are provided with end pieces 22 and 23, the latter being mounted upon a pair of shafts 25 and 26, each extending practically the full width of the machine. The end pieces 22 and 23 carry pins 27, which extend through slots 28 with which the rocking plates 10 are provided, as may be understood from Figure 2.

A pair of casing members are shown at 29 and 30, and are pivotally mounted upon the bearing plate 9. These casing members are of such form and size that they may be brought together face to face as indicated in Figures 1 and 2, and may be swung apart and brought together back to back as indicated in Figure 4.

The casing members are provided with fastenings 31, 32 and 33, for holding them together in their different positions.

The casing members are further provided with guide rods 34. A pair of strops are shown at 35 and 36, and arranged as shown. One of these strops, say the one numbered 35, is made of leather, the other one being made of canvas. A pair of yokes 37 are connected with the rocking plate 10 and connecting plates 15, as indicated in Figure 3, for the purpose of strengthening these parts and yet allowing them a slight de-

gree of flexibility, due to the nature of the spring sheet material of which they are composed.

Whenever the strops 35 and 36 shown in Figure 1 are drawn in such direction as to rock the rocker 21 slightly in a clockwise direction according to this figure, the shaft 26 is moved to the right according to this figure, and has a tendency to carry with it the rocking plates 11, the flexibility of the mountings for this plate being adequate to allow it a slight movement within the casing. This causes the blade 19 to move slightly in a counter-clockwise direction according to this figure, and thus be brought into engagement with the strop 36. The strops being now moved in the opposite direction, so as to rock the rocker 21 slightly in a counter-clockwise direction, a slight torque is produced in the rocking plates 11, the result being that the blade 19 is thereby forced to the left according to this figure, and into engagement with the adjacent surface of the strop 16. This step is repeated as often as desired, the blade 19 thus being sharpened by means of the strop 36.

Next the two casing members 29 and 30 are swung apart like the leaves of a book, the fastening members holding them together being disconnected for this purpose. This done the casing members are swung angularly around as indicated in Figure 4, the strops and various parts immediately associated therewith being now brought into positions indicated in Figure 6. The bail 7 is at practically the same instant swung into its reverse position, as indicated in this figure. The bail 7 being now suspended from a nail or the like, the machine is again ready for use. This time, however, it is the blade 18 instead of the blade 19 which is in position to be acted upon by a strop, and it is the strop 35 and not the strop 36 which is now adapted to be brought against the blade. The operator next, by drawing the two strops as a unit back and forth, causes the strop 35 to act first on one side of the blade and then upon the opposite side thereof, until the blade is sharpened, or otherwise in proper condition to be removed.

In the particular use of the machine as just described, two razor blades are placed in position and are acted upon one at a time. However if the operator so prefers he can insert a single blade only, and sharpen that blade, after which he can shift that blade from one of the blade holders to the other, and at the same time reverse the machine as above described in connection with Figure 4. This done, he can sharpen the same blade again, but with a strop different from the one he had first used upon that blade.

My device is made of materials readily produced in large quantities, and the va-

rious parts are of such form as to render them relatively easy to standardize. Moreover the device is quite well adapted for use with razor blades of many different kinds.

I do not limit myself to the precise construction shown, as variations may be made therein without departing from my invention, the scope of which is commensurate with my claims.

Having thus described my invention what I claim as new and desire to secure by Letters Patent is as follows:

1. A razor double stropping machine comprising a pair of blade holders extending in opposite directions, a pair of rocking members connected with said blade holders for the purpose of shifting the angular directions in which said blade holders extend, a pair of strops, and means controllable by the operator for bending said pair of strops around one of said blade holders in order to use one of said strops on a blade, and for bending said pair of strops around the other of said blade holders in order to use the other of said strops upon a blade.

2. A device of the character described comprising a pair of casing members pivotally mounted to swing in opposite directions and thus brought together at one time face to face and at another time back to back, a pair of blade holders common to said casing members, the casing members being so connected with the blade holders that either of said blade holders may be brought within the casing, a pair of strops of different character, each extending through both of said casing members, so that the swinging of said casing members carries one strop out of operative relation with one of said blade holders and carries the other of said strops into operative relation with the other of said blade holders.

3. In a device of the character described, the combination of a pair of casing members pivotally connected in such manner that they may be brought together face to face or back to back, a pair of blade holders connected with said casing members and so arranged that one of said blade holders is enclosed by said casing members when brought together face to face, the other of said blade holders being enclosed by said casing members when said casing members are brought together back to back, a pair of strops extending through said casing members in such manner that when said casing members are brought together face to face one of the strops is brought into proximity to one of said blade holders, and when the members of said casing are brought together back to back the other of said strops is brought into proximity to the other of said blade holders, and a pair of rocking devices

carried by said casing members and connected with said blade holders, and rocking devices being also connected with said strops, and controllable thereby for shifting 5 the position of said blade holders relatively to said strops.

4. In a device of the character described the combination of a bail, a pair of casing members mounted upon said bail and arranged 10 to swing in opposite directions so that they can be brought together face to face or back to back, and razor stropping mechanism connected with said casing members and comprising a pair of blade holders 15 and a pair of strops, both strops extending through the casing in such manner that when the casing members are brought together face to face they enclose one of the

blade holders, and when they are brought together back to back they enclose the other 20 of said blade holders.

5. In a device of the character described the combination of a pair of blade holders extending in opposite directions, a pair of strops of different character extending intermediate 25 said blade holders, and means controllable by the operator for bending said pair of strops in opposite directions, so as to first bring one of the strops into proximity to one of the blade holders, and then to bring the other of said strops into 30 proximity to the other of said blade holders.

Signed at New York city, in the county of New York and State of New York, this 27th day of November, 1922.

HARRY SEIGMAN.
